HOYT C. HOTTEL, OF CAMBRIDGE, MASSACHUSETTS

FLUID PRESS

Application filed November 7, 1928. Serial No. 317,805.

This invention relates broadly to improvements in fluid-pressure presses or jacks and more specifically to presses for forming plastic materials in molds.

5 In the shaping of plastic materials in molds, it is customary to employ a press for forcing or compressing the material into the mold, the press acting in one direction for accomplishing this step. When the material, 10 the mold and core, or the position of the press is such that a force is required to return the piston to its initial position, it is customary either to rely on gravity or to place in engagement with the piston of the press a fluid-pressure jack, or the like, which will act in the opposite direction to return the piston to its starting position. Gravity frequently is 15 insufficient to return the ram, at least with adequate speed, for quantity production work, while the use of an additional unit, such as an overhead fluid-pressure jack when the press is of the vertical type, requires room which frequently is not available.

20 It is the primary object of this invention, therefore, to provide a press or jack which will permit of its piston being forcibly and rapidly returned to its starting position.

25 A further important object of the invention is to provide a work performing unit of the above mentioned type which possesses the further advantage that the pressure exerted during the power or the material pressing stroke is greater for a given piston diameter and hydraulic pressure than in the case of a simple press.

30 Another object of the invention is to provide a fluid-pressure press or jack which is of exceedingly simple construction and 40 which may be expeditiously taken apart to permit repairs, such as the renewal of packing or the like.

35 Other objects and advantages of the invention will be apparent during the course of the following description.

45 In the accompanying drawing forming a part of this specification and in which like numerals are employed to designate like parts throughout the same—

50 Figure 1 is a vertical sectional view of a

fluid-pressure press or jack embodying this invention, and

Figure 2 is a transverse sectional view taken through the structure shown in Figure 1.

55 Referring to a preferred embodiment of the invention shown in the accompanying drawing, the numeral 5 designates a cylinder closed at one end by a wall 6 which is extended radially to form a supporting flange 60. The cylinder bore is increased in diameter at 8 to form a seat for a packing ring 9 held in place by a compressing ring 10. The ring 10 is of angular formation in cross section to provide a packing engaging flange 65 11 which is forced axially of the cylinder by means of bolts, or the like, 12 threaded into the end portion of the cylinder 5.

70 The end wall 6 of the cylinder is formed with an aperture 13 enlarged at 14 to receive the flanged end 15 of a rod 16 which projects axially through the interior of the cylinder 5. Bolts, or the like, 17 are employed for connecting the rod 16 to the cylinder wall 6. It is to be understood that this rod may 75 be formed integral with the wall 6 if so desired.

77 A body 18 is shaped exteriorly to properly fit within the bore of the cylinder 5 for axial movement therein. It is to be understood 80 that the packing ring 9 will prevent leakage between the walls of the body 18 and the cylinder 5. This body will be termed a combined movable piston and cylinder structure in view of the fact that it acts as a movable 85 piston for the cylinder 5 and as a movable cylinder for a piston, which will be described at a later point, fastened to the rod 16. This combined piston and cylinder structure includes an axial bore 19 apertured at 20 for 90 slidably receiving the rod 16. The aperture 20 is increased in diameter to form a pocket to receive a packing ring 21 held in place by the compressing ring 22. This ring is adjustably secured to the structure 18 by means 95 of bolts or the like 23.

97 The free end of the rod 16 is reduced and externally threaded to receive the sectional piston head 24 which includes the mating sections 25 and 26. The adjacent faces of 100

these sections are cut away to receive the packing ring 27 as best illustrated in Figure 1. The said piston head is secured to the reduced end of the rod 16 by means of a nut or the like 28.

5 The open end of the bore 19 of the combined piston and cylinder structure 18 is closed by a plug 29. This plug is axially recessed at 30 to accommodate the piston head securing nut 28 and the projecting end portion of the rod 16. The plug is flanged at 31 to accommodate the securing bolts 32, the said bolts thereby being arranged outside of the wall of the bore 19.

10 It now will be noted that the structure above described forms an expandible structure including an expandible chamber 33 between the inner end of the body 18 and the wall 6, a second expandible chamber 34 between the inner face of the piston head 24 and the ring or abutment 22, and a third expandible chamber 34a between the outer face of the piston 24 and the plug or abutment 29. For the purpose of simultaneously admitting 15 fluid-pressure into the expandible chamber 33 and the expandible chamber 34a, a connection 35 communicates with the chamber 33 and a passageway 36 is formed in the wall of the combined piston and cylinder structure 18. This passageway 36 extends from the inner face of the structure 18 to the outer end portion of the bore 19, entering the expandible chamber 34a adjacent to the plug 29. Any suitable form of valve 20 structure, not shown, may be inserted in the connection 35 to permit this connection to be selectively supplied with fluid-pressure or placed in a direct communication with the atmosphere for exhausting the two chambers.

25 For the purpose of supplying fluid-pressure to the expandible chamber 34, the rod 16 is provided with a passageway 37 which communicates at its outer end with the said chamber 34 and at its inner end with a connection 38 extending through the cylinder 5 to the exterior thereof. A suitable packing structure 39 prevents leakage around the connection 38.

30 The operation of this device may be described as follows: For the purpose of expanding the structure, that is, causing the combined piston and cylinder structure 18 to move axially outwardly with respect to the cylinder 5, fluid-pressure is admitted to the chambers 33 and 34a through the connection 35 and the passageway 36, respectively. It will be noted that during this stroke or 35 movement of the structure 18 greater pressure is exerted for a given piston diameter and hydraulic pressure than in the case of a simple press or jack. The total area used in calculating the force tending to move the structure 18 is the inside end area of the

structure 18, minus the cross sectional area of the rod 16, plus the end area of the stationary piston head 24.

40 For forcibly returning the structure 18 to its innermost or starting position, the connection 35 is placed in communication with the atmosphere for exhausting the chambers 33 and 34a, and fluid-pressure is admitted to the chamber 34 by means of the passageway 37 and the connection 38. It will be noted that during the upward movement of the combined structure 18, the chamber 34 is exhausted through the passageway 37 and connection 38.

45 It is to be understood that the form of this invention herewith shown and described is to be taken as a preferred example of the same, and that various changes in the shape, size and arrangement of parts may be resorted to without departing from the spirit 50 of the invention or the scope of the subjoined claim.

55 I claim:

60 A device of the type described comprising a cylinder closed at its inner end and open at its outer end, an abutment fixed with respect to said cylinder in spaced relation to the closed inner end thereof, a ram slidable within said cylinder providing an expandible chamber between the closed inner end 65 of said cylinder and the adjacent end of said ram, said ram having a bore receiving said abutment, means closing the ends of said bore whereby separate expandible chambers are provided between said abutment and the inner and outer ends of said bore, respectively, means whereby fluid is adapted to be admitted to the chamber between the closed inner end of said cylinder and the adjacent end of said ram for forcing the 70 ram outward relative to the cylinder, said ram having a duct formed therein providing constant communication between said last mentioned chamber and the chamber between said abutment and the closing means 75 for the outer end of said bore, and means whereby fluid is adapted to be admitted to the chamber between said abutment and the inner end of said bore to effect inward movement of the ram relative to the cylinder.

80 In testimony whereof I hereunto affix my signature.

HOYT CLARKE HOTTEL.
